DOOR COUNTERBALANCE

Filed Sept. 14, 1945

UNITED STATES PATENT OFFICE

2,550,161

DOOR COUNTERBALANCE

George C. Pearce, Dayton, Ohio, assignor to General Motors Corporation, Dayton, Ohio, a corporation of Delaware

Application September 14, 1945, Serial No. 616,361

7 Claims. (Cl. 126—191)

1

This invention relates to door counterbalances. An object of this invention is to provide a counterbalancing means for the door of a range, or the like, which is simple in construction and effective in operation.

Another object of this invention is to provide a counterbalancing means for a door which uses a single spiral tension spring for counterbalancing the door and for maintaining it slightly ajar or fully closed.

Further objects and advantages of the present invention will be apparent from the following description, reference being had to the accompanying drawings, wherein a preferred form of the present invention is clearly shown.

In the drawings:

Fig. 1 is a vertical cross-section along one side of the oven, taken along the line 1—1 of Fig. 2;

Fig. 2 is a cross-section taken along the line 2—2 of Fig. 1;

Fig. 3 is a horizontal cross-section taken along the line 3—3 of Fig. 1; and

Fig. 4 is a cross-section of a portion of Fig. 1, showing the parts in a different position.

A range embodying my invention may include a main body 10, which may include an oven liner 11, a door jamb 12 and side bottom channels 13. These members may be of any suitable construction, and the specific form shown is merely by way of illustration.

The main body may carry door brackets 14, which conveniently may be attached to the channels 13 by means of the bolts 15. The bracket 14 has a hook-shaped extension 16 passing through the slot 12a in the door jamb 12. The extension 16 is provided with an opening for the reception of a hinge pin 17 in the door 18.

The door 18 may be of any suitable construction, and conveniently may have an outer panel 19 and an inner panel 20. The hinge pin 17 is secured at one end by the screw 21 to the panel 20 and passes through the extension 16 and a portion 22 of the door counterbalance arm 23 of the door 18. The door counterbalance 23 may be attached to either of the panels 19 or 20, and is shown attached to the panel 19. In general the bracket 14, pin 17 and door construction may be of the character disclosed in the patent to F. H. McCormick 2,378,421, patented June 19, 1945.

The door may be counterbalanced by duplicate spiral springs 30, at each side of the door opening. One end or portion 31 of the spring 30 is secured to the counterbalance arm 23, being hooked into the opening 32. The intermediate

2

portion 33 of the spring 30 rides over a pulley 34, and the other end or third portion 35 of the spring 30 may be secured to the main body of the range by means of the bolt 36. The pulley 34 is carried by a pulley-carrying member 37, which may include one or two levers 38 hinged at 39 to the bracket 14. The levers carry the pulley 34 by means of pin 34a. In addition, they carry a wedge rider 40, which may be in the form of a pin or roller secured to the levers 38. The spring 30 and pulley-carrying member 37 may be duplicated at each side of the door, if desired.

The arm 23 is provided with a wedge 41 which rides over the wedge rider 40. When the door is fully closed, the upper portion 42 of the wedge 41 engages the rider 40, as shown in Fig. 1. When the door is slightly ajar, for broiling purposes or the like, the lower portion 43a of the wedge 41 rides against the wedge rider 40, as shown in Fig. 4. The reaction of the spring 30 on the pulley 34 and levers 38 is such as to hold the wedge 41 in either of the positions shown in Figs. 1 or 4, the door snapping from one position to the other as the point of the wedge 41 passes over the rider 40.

An abutment 43 is provided on the arm 23, which is adapted to engage the top 44 of the slot 45 through which the arm 23 passes the door jamb 12. When the door is in fully open horizontal position, the abutment 43 engages the top 44. In this position the tension of the spring 30 is not sufficient to pull the door upwardly; but does exert a counterbalancing action.

Insulation 46 may be placed around the oven liner 11. If desired a shield 47 may be secured to the channel 13 for the door jamb 12 for the purpose of preventing the insulation from falling into engagement with the arm 23.

While the form of embodiment of the invention as herein disclosed, constitutes a preferred form, it is to be understood that other forms might be adopted, as may come within the scope of the claims which follow.

What is claimed is as follows:

1. A device of the character described comprising a main body having a wall provided with an opening, a door hinged to said body adjacent said opening and adapted to close said opening, a pulley lever hinged to said main body, a pulley on said lever, tension spring means having one portion secured to said door, an intermediate portion passing over said pulley and a third portion secured to said body, said spring means imparting a bias to said lever, and means on said door and lever responsive to said bias and coop-

eratively holding said door both in closed or slightly open positions.

2. A device of the character described comprising a main body having a wall provided with an opening, a door hinged to said body adjacent said opening and adapted to close said opening, a pulley lever hinged to said main body, a pulley on said lever, a counterbalance arm on said door, tension spring means having one portion secured to said arm, an intermediate portion passing over said pulley and a third portion secured to said body, said spring means imparting a bias to said lever, and means on said arm and lever responsive to said bias and cooperatively holding said door both in closed or slightly open positions.

3. A device of the character described comprising a main body having a wall provided with an opening, a door hinged to said body adjacent said opening and adapted to close said opening, a pulley lever hinged to said main body, a pulley on said lever, a counterbalance arm on said door, tension spring means having one portion secured to said arm, an intermediate portion passing over said pulley and a third portion secured to said body, said spring means imparting a bias to said lever, a wedge on said arm, and a wedge rider on said lever, said wedge and wedge rider cooperating in response to said bias to hold said door both in closed or slightly open positions.

4. A device of the character described comprising a main body having a wall provided with an opening, a door hinged to said body adjacent said opening and adapted to close said opening, a pulley-carrying member hinged to said body, a pulley on said member, a counterbalance arm member on said door, tension spring means having one portion secured to said arm member, an intermediate portion passing over said pulley and a third portion secured to said body, said spring means imparting a bias to said pulley-carrying member, a wedge on one of said members, and a wedge rider on the other of said members, said wedge and wedge rider cooperating in response to said bias to hold said door both in closed or slightly open positions.

5. A device of the character described comprising a main body having a wall provided with an opening, a door hinged to said body adjacent said opening and adapted to close said opening, a pulley-carrying member hinged to said body, a pulley on said member, a counterbalance arm member on said door, tension spring means having one portion secured to said arm member, an intermediate portion passing over said pulley and a third portion secured to said body, said spring means imparting a bias to said pulley-carrying member, a wedge on said counterbalance arm

member, and a wedge rider on said pulley-carrying member, said wedge and wedge rider cooperating in response to said bias to hold said door both in closed or slightly open positions.

5 6. A device of the character described comprising a main body having a wall provided with an opening, a door hinged to said body adjacent said opening and adapted to close said opening, a pulley-carrying member hinged to said body, 10 a pulley on said member, a counterbalance arm member on said door, tension spring means having one portion secured to said arm member, an intermediate portion passing over said pulley and a third portion secured to said body, said spring 15 means imparting a bias to said pulley-carrying member, a wedge on one of said members, a wedge rider on the other of said members, said wedge and wedge rider cooperating in response to said bias to hold said door both in closed or 20 slightly open positions, and an abutment on said counterbalance arm member engaging said main body when said door is fully open.

7. A device of the character described comprising a main body having a wall provided with an opening, a door hinged to said body adjacent said opening and adapted to close said opening, a pulley lever hinged to said main body, a pulley on said lever, a helically wound tension spring of substantially uniform diameter having one end secured to said door, an intermediate portion passing over said pulley and its other end secured to said body, said spring imparting a bias to said lever, and means on said door and lever responsive to said bias and cooperatively holding said door both in closed or slightly open positions.
